Nathaniel Waterman, of Boston, Mass.
Letters Patent No. 1043, dated Aug. 17, 1858.

The schedule referred to in these Letters Patent and making part of the Same.

To all Persons to whom these presents shall come:

Be it known that I, Nathaniel Waterman, of Boston, in the County of Suffolk, and State of Massachusetts, have invented a new Ornamental design for Roll Pans, and I do hereby declare that the same is fully represented in the accompanying drawings, of which

Figure 1. is a top view.

Figure 2. a side view.

Figure 3. a longitudinal, and

Figure 4. a transverse section of such.

In carrying out the design pans A.A. are joined at their upper edges by a connection piece a, and each of the pans has the peculiar shape, on its top, bottom and sides as shown at b, c, d, & in the drawings. The set of roll pans is to be used for baking bread in small rolls.

I claim the design substantially as described and exhibited in the drawings.
